VENTILATED ENGINEER'S CAP

Robert Klein, Brooklyn, N. Y., assignor to Bell Cap Company, New York, N. Y., a co-partnership composed of Abraham Herskowitz, Samuel Bell, Morris Goldberg, and Robert Klein

Application December 11, 1934, Serial No. 756,923

8 Claims. (Cl. 2—195)

This invention relates to caps and particularly, to that type known as "railroad" or "engineer's" caps.

My invention contemplates the provision of a cap provided with efficient ventilating means inserted in the crown of the cap and formed in the shape of and folded in the same manner as that portion of the crown which it replaces, and which does not in the least adversely affect the flexibility, wearing qualities or appearance of the cap in which it is used, but on the contrary, considerably enhances the appearance and wearing properties of the cap besides making the cap more comfortable for the wearer.

My invention further contemplates the replacement of a selected section of the closely woven textile fabric crown of a cap with textile fabric loosely woven to provide a multiplicity of ventilating openings therein, but having substantially the same strength and flexibility as that of the closely woven crown fabric, and adapted to be sewn in place in the same manner as the crown fabric, as well as to be folded and pleated in the same manner as the crown fabric.

My invention further contemplates the provision of one or more fabric ventilating sections in the one-piece crown of a cap above the sweatband thereof, so arranged and of such size as to adequately ventilate the head of the wearer above the sweat-band and to permit the circulation of air across the top of the head when the cap is being worn.

The various objects of my invention will be clear from the description which follows and from the drawing, in which,

Fig. 1 is a side elevation of my improved cap, it being understood that the other side of the cap, not shown, is of the same construction.

Fig. 2 is a fragmentary combined vertical section (taken on the line 2—2 of Fig. 1) and perspective view of a portion of the cap.

Fig. 3 is a front elevation of a modified form of my improved cap showing the ventilating section arranged at the front of the cap to replace the front pleat of the crown fabric.

Fig. 4 is a similar view of another modified form of my improved cap wherein a pair of spaced unpleated ventilating sections is used, each of which is arranged between the front and side pleats of the cap, and being of sufficient height to perform its proper ventilating function.

Fig. 5 is a fragmentary view on an enlarged scale of the ventilating fabric used in the crown of the cap.

Fig. 6 is a fragmentary enlarged horizontal sec-

tion, taken on the line 6—6 of Figs. 1 and 3, but with the stitching for the upper edge of the ventilating section omitted for the sake of clarity and to avoid confusion, showing the pleat formed in the ventilating section and the plurality of thicknesses provided, and showing also, the stitching for securing the side edge of the ventilating section in place.

In that practical embodiment of my invention which I have shown by way of example, my improved ventilating means has been applied to a so-called "railroad" cap of the type used by engineers and mechanics in railroad shops and elsewhere to protect the head of the wearer. Since such caps are worn by men who are physically active, the perspiration induced by the cap frequently causes discomfort. I have therefore provided effective means, economical to manufacture and simple in construction for adequately ventilating the head of the wearer and the interior of the cap while the cap is being worn.

As illustrated, the cap includes a visor 9, and a sweatband designated generally by the numeral 10 and comprising the outer sweatband section 11 and the inner similar sweatband section 12. Both of said sections are infolded along their lower and upper edges as at 13 and 14, respectively. The visor 9 is inserted between the infolded lower edges 13 of the sections 11 and 12, said infolded edges being secured together by suitable stitching 15, 16 passing through the sections and the infolded portions thereof, and through the visor. The upper infolded edges 18 and 19, respectively, of the respective sections 11 and 12 are, however, first sewn together in reverse position by the stitching 17 with the ventilating fabric 20 inserted between said infolded portions. On reversal of the sections, the stitching 17 is concealed, and the final stitching 15, 16 made.

In the crowns of caps of this type, it is at present customary to provide the front pleat 21, the rear pleat 22 and similar side pleats intermediate the front and rear pleats.

Each of the pleats is of about the same height as the crown and is of substantial width about equal to its height, having parallel edges 23 and 24 (see Fig. 4). The pleat is formed by overlapping or puckering the fabric of the crown which is made of a single piece of comparatively closely woven material consisting of comparatively fine threads. To form the ventilating sections, however, as shown in Fig. 1, the entire pleat together with a triangular section at each side of the pleat are omitted from the otherwise

one-piece crown and a section of suitable loosely woven ventilating textile fabric material is arranged in the opening in the crown thus formed.

I prefer to use for the ventilating sections as 5 **20**, a woven textile fabric material having water-repellent properties and so woven as to be not only strong, durable and flexible to substantially the same extent as the remaining closely woven fabric of the crown but also so woven as to form 10 a multiplicity of interstices or apertures, through which air may enter and leave the interior of the cap. As shown particularly in Fig. 5, the ventilating fabric comprises a series of comparatively coarse or thick warp threads **26** and weft threads **27** spaced considerably apart to form 15 comparatively large openings, the openings being partially closed by the interwoven coarse or heavy thread **28** twisted about the warp and weft threads and serving to prevent such displacement of said warp and weft threads under such 20 stress as might tend to change the sizes or shapes of the openings.

Each of the side ventilating sections **20** as shown in Figs. 1 and 6, comprises the pleat **30** 25 and the exposed triangular sections **31** and **32** arranged respectively in front of and at the rear of the pleat. Between the rear edge **33** of the pleat **30** and the front inclined edge **34** of the rear triangular exposed side section **32**, there is 30 thereby arranged three thicknesses of material.

Similarly, between the front edge **36** of the pleat **30** and the rear edge **37** of the front triangular exposed section **31**, there is also provided 35 three thicknesses of material. By so providing a multiplicity of thicknesses, the ventilating section may be firmly secured to the sweatband where the stress thereon is greatest and further, substantially the same degree of rigidity and flexibility as there is in the remaining fabric crown 40 pleats **21** and **22** is provided in the ventilating section, whereby the proper shape of the cap crown is maintained, though permitting the cap to be folded up in the customary manner when it is to be carried about.

The blanks from which the ventilating sections **20** are made are each trapezoidal in form 45 before and after being sewn in place, being provided with inclined ends to permit the formation of the pleat or pucker therein. When the pleated section **20** is secured in place, the initially inclined edges **38** and **39** of the blank are secured between the infolded portions **18** and **19** of the sweatband sections **11** and **12** by the stitching **41** as hereinbefore described, said edges **38** and **39** being aligned with the remainder of the bottom edge of the blank. The ventilating section **20** is secured to the crown along the inclined edge **41** thereof at the inclined edge of the opening in the crown, the corresponding edge portion **42** of the section being secured to the crown 55 along the front inclined edge **43**, while the remainder of the section is secured to the top edge **44** of the opening formed in the crown for the reception of the ventilating section.

To secure the top edge of the section in place 60 in its proper position, said edge is laid in reverse position on the crown edge surrounding the opening into which the ventilating section is to be arranged, and then the marginal portions of suitable width of the ventilating section and the crown fabric are secured together by means of suitable stitching such as the overlocking stitching **45** (Figs. 2 and 6). The parts are then turned back into their final positions and again 65 secured by the stitching **46** passing through the

ventilating section and through the infolded flap **47** of the crown fabric and through the outer crown fabric **48**.

After the ventilating sections have been sewn in place at the sides of the cap, it will be seen 5 that said ventilating sections stand above the sweatband in such position that they are not in contact with any part of the head of the wearer whereby the air may enter freely through the interstices **50** of said ventilating sections and 10 circulate about the head and throughout the interior of the cap. The head of the wearer is thereby kept comparatively cool though adequately protected from dirt, grease, rain and the like. It will also be noted that by reason of the 15 comparatively coarse threads from which the ventilating sections are formed and the peculiar weave thereof, said sections are just as flexible but not more so than the crown fabric and therefore maintain the proper shape of the cap just 20 as though the cap were made entirely of the closely woven crown fabric.

In that form of my invention shown in Fig. 3, the ventilating section **51** replaces the closely woven fabric pleat **21** as well as the triangular portions of the crown fabric adjacent the pleat in the same manner as described in connection with the side ventilating section **20**.

A similar rear ventilating section may be used, if desired, to replace the pleat **22** (Fig. 1) and 30 to insure circulation of air from the front to the rear of the cap and vice versa. The construction and means for securing the section **51** in place being identical with that hereinbefore described 35 in connection with the section **20**, the description thereof need not be repeated.

As shown in Fig. 4, the ventilating sections **52** and **53** may each be arranged between the front fabric pleat **21** and the side fabric pleats **54** and **55** respectively. In that case, the ventilating 40 sections are substituted for the unpleated crown fabric in such a manner as to induce a circulation of air at the front of the cap above the head of the wearer and thereby to induce circulation throughout the entire interior of the cap. Since 45 the means for securing the edges of the sections **52** and **53** to the crown and to the sweatband are similar to that hereinbefore described, the description thereof need not be repeated.

It will be seen that I have provided a simple 50 though extremely economical and efficient cap designed to permit circulation of air about the top of the head of the wearer and arranged above the sweatband of the cap and having the same flexible and shape-supporting properties as the 55 fabric of the remaining crown of the cap, being in addition water-repellent and presenting an excellent appearance and therefore well adapted to meet the severe requirements of practical use.

While I have shown and described certain 60 specific forms of my invention, I do not wish to be understood as limiting myself thereto since I intend to claim my invention as broadly as may be permitted by the state of the prior art and the scope of the appended claims.

I claim:

1. In a cap, a sweatband comprising a pair of separate similar sections, a pleated crown of closely woven fabric, said crown having an opening therein, and a pleated section of loosely woven fabric providing interstices therein arranged in the opening and secured along one edge thereof to and between the sweatband sections and along the other edge thereof to the edge of the opening in the crown.

2. A ventilating cap comprising a sweatband having an outer and an inner section each having infolded upper and lower edges, a closely woven fabric crown provided with a multiplicity of pleats 5 each of substantially the height of the crown and each of substantially the same width as the height thereof, said crown having a trapezoidal opening therein extending over an area equal to the area of one of said pleats together with additional 10 triangular side extensions, the edges of the crown adjacent the opening being infolded, and a section of loosely woven fabric comprising a ventilating area arranged in said opening, said section being pleated to correspond to the remaining 15 pleats of the crown and thereby providing three thicknesses of material at the overlapping portions of the pleat therein, and having exposed triangular extensions of a single thickness, the upper edge of said ventilating section being secured 20 to an infolded edge of the opening in the crown by overlapping stitching and by an additional line of stitching passing through said section and through the crown and the infolded edges thereof, and the lower edge of said section being secured 25 between the upper infolded edges of the sweatband sections by a line of stitching passing through said sections and the infolded edges thereof.
3. In a cap provided with a pleated crown, a visor, and a sweatband joining the crown and the visor, a pleated ventilating section in the crown providing a plurality of thicknesses of ventilating material at the pleat thereof, and spaced triangular areas of a single thickness of ventilating 30 material at the remaining portions thereof, overlocking stitching securing the upper edge of said section to the adjacent edge of the crown, and concealed stitching securing the lower edge of the ventilating section to the sweatband, said 35 ventilating section being formed of loosely woven fabric having substantially the same cap-shaping properties as the material of the crown.
4. In a cap, a fabric sweatband comprising an outer sweatband section and a similar inner sweatband section, a pleated crown having its 40 lower edge inserted between said sections and stitched thereto, and a pair of spaced ventilating sections in the crown, each of said ventilating sections being of substantially the same height as that of the pleats therein, and of substantially the same width along one of its edges as the height thereof, and each of said ventilating sections comprising a series of warp threads and weft threads 45 interwoven with the warp threads to provide substantially square interstices therebetween, and a 50 twisted thread interwoven with the warp and weft threads and maintaining said threads against displacement to maintain the sizes of the openings in said section unchanged under stress put upon the cap.
5. In a cap, a pleated crown of a single piece of material, a sweatband secured to the lower edge of said crown, part of the material of said crown being omitted to provide an opening therein, and a textile fabric ventilating section secured in the opening by stitching securing its upper edge to the crown and its lower edge to the sweatband, said ventilating section comprising loosely woven warp and weft threads providing a multiplicity of openings therein, and said section being of substantially the same height as the pleats in the crown and substantially of the same width as said pleats along at least one edge of said section.
6. In a cap, a one-piece fabric crown having a plurality of spaced pleats therein, a sweatband comprising a pair of similar sections, the lower edge of the crown being secured by concealed stitching between the upper edges of said sweatband sections, and a ventilating section of substantially the same height and width as that of the pleats of the crown secured along its upper edge to the crown and along its lower edge between the sweatband sections, said ventilating section comprising textile fabric woven of thicker 30 threads than that of the crown fabric and thereby having substantially the same flexibility and cap-supporting properties as the crown fabric.
7. In a cap provided with a pleated crown, a visor, and a head band joining the crown and the visor, a pleated ventilating section in the crown providing a plurality of thicknesses of ventilating material at the pleat thereof, stitching securing the upper edge of said section to the adjacent edge of the crown, and concealed stitching securing the lower edge of the ventilating section to the head band, said ventilating section being formed 35 of loosely woven fabric.
8. In a cap, a one-piece fabric crown having a plurality of spaced pleats therein, a head band at the lower edge of the crown, concealed stitching securing the lower edge of the crown to the upper edge of the head band, and a ventilating section inserted in the crown and secured along its upper edge to the crown and along its lower edge to the head band, said ventilating section comprising textile fabric woven of thicker threads 40 than that of the crown fabric.

ROBERT KLEIN. 55
